MULTISTAGE COMPRESSOR

Pietro Maniscalco, Toledo, Ohio

Application March 4, 1938, Serial No. 193,967

7 Claims. (Cl. 230—192)

This invention relates to a multistage compressor.

One of the objects of this invention is to provide a durable, economical and efficient compressor whereby a high stage of compression can be speedily obtained.

Another object of this invention is to provide a multistage compressor having its parts arranged in balanced relation, producing a smoothly operating and economical construction.

A further object of this invention is to provide an efficient compressor of this kind which is especially adapted for use in refrigeration and air conditioning devices.

These and various other objects and advantages are attained with this invention, as will become apparent from the following description, taken in connection with the accompanying drawings wherein the invention is illustrated in its preferred form, it being apparent that other forms of construction may be adopted for carrying out the objects and purposes of this invention.

In the drawings:

Fig. 1 is a plan view illustrating this invention in its preferred form of construction, as embodied in a pair of cooperating multistage compressors with part of the cover broken away.

Figs. 2 and 3 are enlarged vertical sectional views, taken respectively on lines 2—2 and 3—3 of Fig. 1.

Fig. 4 is a diagrammatic view illustrating this improved compressor utilized in a refrigeration unit.

In the drawings this invention is illustrated in its preferred form of construction and as embodied in a pair of companion compressor units 10 and 10' which are similar in construction and are mounted parallel and closely together on a base 11, as indicated in Figs. 1 and 2, so as to be driven together by the same driving means, as for example the motor 12 shown in Fig. 4.

The pair of compressor units 10 and 10' comprise respectively, a pair of piston units 14 and 14' which are mounted to reciprocate on the base 11, preferably by means of a pair of ribs 15 and 15' provided on the under side of said pair of units 14 and 14' respectively, and travelling on a pair of guide tracks 16 and 16' provided on the top of a pair of parallel blocks 17 and 17' respectively, which arise from and are integral with said base 11.

These compressor units 10 and 10' are alike in construction and operation, and the unit 10' 55 comprises the same parts as the unit 10, the cor-

responding parts thereof being therefore designated herein by the same reference numbers but having the prime character added thereto. The description of said unit 10 thus suffices and applies equally to said unit 10'.

The piston unit 14 comprises a main central body or block 20 provided with a larger piston 21 at one end and a smaller piston 22 at the opposite end. A skirt 23 extends around the main part of piston 21, and a skirt 24 extends around the main part of piston 22, said skirts being provided by forming annular channels 25 and 26 between said pistons and skirts as best shown in Fig. 3.

A pair of standards 27 and 28 are mounted upon the base, adjacent the ends of piston unit 14, and a similar pair of standards are mounted on the base adjacent the ends of the companion piston unit 14'. Said standards 27 and 28 contain at their upper ends a pair of integral cylinder heads 29 and 30 respectively, which are provided with integral cylinders 31 and 32 arranged to engage in said annular channels 25 and 26 respectively, and to have the pistons 21 and 22 sliding therein. Each channel is slightly larger than the thickness of its cylinder, and is preferably tapering or enlarged outwardly, to avoid any air from becoming entrained or blocked at the inner end of the channel and thereby retard the movement of the cylinder therein.

A fluid channel 34 extends thru the piston unit 14, and at its ends it has a pair of pockets 35 and 36 located in the ends of pistons 21 and 22 respectively, said pockets being provided with an inlet valve 37 and an outlet valve 38 respectively, so that the compressed air will flow only from the pocket in the larger piston to the pocket in the smaller one.

Pockets 39 and 40 are formed in cylinder heads 29 and 30 respectively, being placed adjacent to the piston pockets 35 and 36, and contain an inlet valve 41 and an outlet valve 42 therein to cooperate with the piston valves 37 and 38 respectively. Ports 43 and 44 extend respectively, from the pockets 39 and 40 thru the cylinder heads, and have the pipes 45 and 46 of the refrigerant circulating mechanism joined thereto. The port 43 with the pocket 39 thus provide a fluid inlet channel in the cylinder head 29, while the pocket 40 and the port 44 provide a fluid outlet channel in the cylinder head 30 of this compressor unit. The other compressor unit 10' is constructed and arranged like this described unit 10, as indicated heretofore.

The means for driving or reciprocating these

two companion piston units preferably comprises a drive shaft 48 mounted in a pair of sleeves 48 and 48' provided on a pair of parallel supporting walls 50 and 50' arising from the intermediate 5 part of base 11. A pulley 51 secured on shaft 48 is driven thru a belt 52 by a pulley 53 on the shaft of said motor 12. A pair of crank arms 54 and 54' are placed off-center at the ends of the drive shaft, as by means of disks 55 and 55', 10 and said arms carry rotary sleeves or bushings 56 and 56' thereon with anti-friction bearing means. These sleeves travel on continuous surfaces provided by vertically elongated pockets 57 and 57' provided on the adjoining sides of the 15 piston bodies 20 and 20' by means of continuous integral flanges 58 and 58' extending laterally from said bodies. Casings 59 and 59' are attached to said walls 50 and 50', and to the side parts of base 11, to cover and protect the 20 compressor mechanisms.

The two compressor units 10 and 10' are mounted parallel and adjacent to each other, and the two piston units 14 and 14' are driven to travel in opposite directions, so that while one unit is 25 moving in the direction of its larger cylinder, on its first stage of compression, the other unit is moving in the direction of its smaller cylinder, on its second stage of compression. The device thus has its parts arranged in balanced relation, 30 and will require and utilize a uniform or balanced application of the driving power; and this improved mechanism functions very efficiently in speedily providing a high stage of compression.

This compressor is especially adapted for use 35 in air conditioning and refrigeration systems; and it is shown in Fig. 1 in conjunction with such a refrigeration system, which includes the motor 12 with a condenser 60, a tank 61, an expansion valve 62, and the refrigeration coil 63, together 40 with the connecting pipes and conduits therebetween.

I claim:

1. A compressor comprising a base having an 45 integral block with a guide track thereon, a piston unit including a body with an integral guide rib thereunder movable along said track and a pair of integral pistons extending in opposite directions from said body, a channel extending thru said body and pistons and provided with 50 check valve means therein, a pair of standards mounted on said base having a pair of cylinders thereon consisting each of a cylindrical member integral on its standard and fitting upon said pistons, one standard having a valved inlet and 55 the other having a valved outlet thereon, and operating means for reciprocating the piston body on the guide tracks with the pistons moving within the cylinders.

2. A compressor comprising a piston unit 60 consisting of a solid block having a pair of solid pistons extending in opposite directions therefrom, a bore extending centrally thru the block and pistons and having a pocket with an inlet valve at one end and a pocket with an outlet valve at the 65 other end, a pair of cylinders on said pistons and means for supporting them stationary, one provided with a valved inlet means and the other with a valved outlet means, and means for reciprocating the unit with its pistons relative to the cylinders.

3. A multistage compressor comprising a base 70 provided with an integral upstanding rib having guide means thereon, a piston unit comprising a solid block having a larger integral piston

at one end and a smaller integral piston at the opposite end, an integral guide rib on said block movable along said guide means, a central bore extending straight thru said block and pistons and provided with an inlet valve in the larger 5 piston and an outlet valve in the smaller piston, a pair of cylinders mounted stationary on said base and provided with inlet and outlet valves to operate with said piston valves, and means for reciprocating the piston unit to slide the pistons 10 in the cylinders.

4. A compressor comprising a base provided with guide means thereon, a piston unit including a substantially solid body provided with integral guide means cooperating with the first said 15 guide means, a pair of oppositely extending integral pistons on said body, a channel extending straight thru said body and pistons and having an inlet valve and an outlet valve at its ends, a pair of standards removably mounted on said base 20 and having each an integral cylinder means thereon consisting of a cylinder head containing a channel therein provided with a pocket at its inner end and having a single integral cylinder 25 extending therefrom wherein one of said pistons reciprocates, one pocket provided with an inlet valve and the other provided with an outlet valve to cooperate with the inlet and outlet valves on said piston channel, and means to reciprocate 30 said pistons in the cylinders.

5. A compressor comprising a base having means thereon provided with a pair of parallel guide tracks, a pair of piston units with guide means reciprocable on said pair of tracks, a pair 35 of oppositely extending pistons on each unit, a pair of stationary cylinders for each pair of pistons, valved channel means extending thru each unit and its pistons, valved inlet and outlet means on each pair of cylinders, a pair of pockets provided on the adjoining sides of said units, a pair 40 of supporting walls extending parallel and integral up from the base between said piston units and provided with bearing sleeves, casing means extending from said walls to the base to house said piston units and cylinders, a drive shaft rotary in said sleeves, and a pair of drive arms extending off-center from the opposite ends of said shaft and operable in said pockets, to reciprocate 45 said pair of units and their pistons in said cylinders.

6. A multistage compressor comprising a base having a pair of integral blocks arising therefrom and provided with a pair of parallel guide tracks thereon, a pair of piston units with integral guide 55 means reciprocable on said tracks, each unit including a solid central body having a pair of oppositely extending integral pistons thereon one being larger than the other, each unit having a pair of solid post-like standards arising from the base and provided with a pair of integral cylinders each in the form of a single cylindrical member extending from its standard and cooperating with the pair of pistons on the unit, valved channel means thru each unit and its pistons, valved 60 inlet and outlet means on each pair of standards and cylinders, a pair of continuous flanges on the two adjacent faces of said pair of units providing guide pockets, means arising between said units and provided with bearing sleeves therein, a drive shaft journaled in said sleeves and provided with means for rotating it, and a pair of drive arms extending off-center from the opposite ends of said shaft and provided with means thereon rotatable in said grooves, whereby to re- 65 70 75

ciprocate said pair of units in reverse directions and provide a balanced mechanism.

7. A multistage compressor comprising a base having a larger cylinder with an inlet valve and 5 a smaller cylinder with an outlet valve mounted stationary in line thereon, also guide means on the base between the cylinders, a unitary piston construction comprising a solid central block having a pair of solid integral pistons thereon including a larger piston at one end and a smaller 10 piston at the opposite end slidable in said larger and smaller cylinders, a guide rib integral on said

block movable along said guide means on the base, a bore extending centrally thru said block and pistons, provided with an inlet valve in the larger piston and an outlet valve in the smaller piston, a continuous integral flange extending laterally from the block and forming a guide pocket having a continuous bearing surface therein, and driving means on the base carrying rotary means adapted to travel along said surface in said pocket, for reciprocating said pistons in 10 said cylinders. 5

PIETRO MANISCALCO.
